UNITED STATES PATENT OFFICE.

WILLIAM H. GINDER, OF HADDONFIELD, NEW JERSEY, ASSIGNOR TO ELECTRO DENTAL MANUFACTURING COMPANY, OF PHILADELPHIA, PENNSYLVANIA, A CORPORATION OF PENNSYLVANIA.

DESIGN FOR AN ELECTRIC FAN.

Application filed March 31, 1928. Serial No. 26,086. Term of patent 14 years.

To all whom it may concern:

Be it known that I, WILLIAM H. GINDER, a citizen of the United States, residing at Haddonfield, in the county of Camden and State of New Jersey, have invented a new, original, and ornamental Design for Electric Fans, of which the following is a specification, reference being had to the accom-

panying drawing, forming a part thereof.

Fig. 1, represents a top plan of the electric fan, and

Fig. 2, represents a side elevation thereof.

I claim:

The ornamental design for an electric fan, substantially as shown.

WILLIAM H. GINDER.
